CLAIM

The ornamental design for a spigot, as shown and described.

DESCRIPTION

FIG. 1 is a perspective view of a spigot;

FIG. 2 is a front view thereof;

FIG. 3 is a rear view thereof;

FIG. 4 is a side view thereof, as taken from the right side of
FIG. 2;

FIG. 5 is a side view thereof, as taken from the left side of
FIG. 2;

FIG. 6 is a top view thereof;

FIG. 7 is a bottom view thereof (the bottom is devoid of
ornamentation);

FIG. 8 is a perspective view of a second embodiment of a
spigot;

FIG. 9 is a front view thereof;

FIG. 10 is a rear view thereof;

FIG. 11 is a side view thereof, as taken from the right side of
FIG. 9;

FIG. 12 is a side view thereof, as taken from the left side of
FIG. 9;

FIG. 13 is a top view thereof; and,

FIG. 14 is a bottom view thereof (the bottom is devoid of
ornamentation).

The broken lines depict portions of the spigot that form no
part of the claimed design.

1 Claim, 8 Drawing Sheets
